SWITCH HOUSING

Kenneth Reiner, Los Angeles, Calif., assignor to Reiner Industries, Inc., Pico Rivera, Calif., a corporation of California

Filed Mar. 9, 1961, Ser. No. 64,203

Term of patent 14 years

(Cl. D26—13)

FIG. 1.

FIG. 2.

FIG. 3.

FIG. 4.

FIGURE 1 is a perspective view of a switch housing embodying my new design.

FIGURE 2 is a front elevation of the switch housing shown in FIGURE 1.

FIGURE 3 is a left side elevation of the switch housing shown in FIGURE 1.

FIGURE 4 is a bottom view of the switch housing shown in FIGURE 1.

The essential features of my design are shown in full lines in the drawing.

I claim:

The ornamental design for a switch housing, as shown and described.
